(57) **CLAIM**

The ornamental design for a touch screen light controller, as shown.

DESCRIPTION

FIG. 1 is a front left side perspective view slightly from below of a touch screen light controller embodying my new design in the off position;

FIG. 2 is a top plan view thereof;

FIG. 3 is a bottom plan view thereof;

FIG. 4 is a rear elevational view thereof;

FIG. 5 is a left-side elevational view thereof;

FIG. 6 is a right-side elevational view thereof;

FIG. 7 is a view similar to FIG. 1 but in the on position and showing a display on the touch screen; and,

FIG. 8 is a front elevational of the touch screen display as shown in FIG. 7.

1 Claim, 8 Drawing Sheets
